United States Patent

Des. 239,691
Patented Apr. 27, 1976

239,691

CONTAINER GRID OR THE LIKE

Harold P. Ashton, Providence, R.I., assignor to Dart
Industries Inc., Los Angeles, Calif.

Filed Jan. 8, 1975, Ser. No. 539,362

Term of patent 14 years

Int. Cl. D7—04

U.S. Cl. D7—130

FIG. 1

FIG. 2

FIG.3

FIG.4

FIG.5

FIG. 1 is a top perspective view of the container grid embodying my ornamental design;

FIG. 2 is a top plan view thereof;

FIG. 3 is a bottom plan view thereof;

FIG. 4 is a side elevational view thereof; and

FIG. 5 is a cross-sectional view thereof taken along line 5—5 of FIG. 3.

I claim:

The ornamental design for a container grid or the like, as shown.
